PORTABLE BULKHEAD

John McMullen, Buffalo, N. Y., and John T. Gallagher, Chicago, Ill.

Application May 3, 1938, Serial No. 205,732

9 Claims. (Cl. 105—369)

This invention relates to portable bulkheads for preventing displacement or shifting of merchandise and is concerned more particularly with bulkheads for use in railway freight cars.

It is an object of this invention to provide bulkheads of simple, sturdy and inexpensive construction characterized additionally by ease of placement and removal.

A further object is to provide portable bulkheads capable of placement and effective use without requiring modification of or addition to the structure in which they are employed.

A further object is to provide portable bulkheads which shall require very little storage space.

A further object is to provide portable bulkheads, the parts of which may be nested so that the bulkheads will be free of projections, but capable of easy handling and requiring a minimum of space for storage when not in use.

A further object is to provide portable bulkheads having merchandise engaging portions and braces, the latter being capable of disposition substantially within the vertical planes defining said portions and of being secured to said portions when the bulkheads are not in use.

Other objects of the invention will become clear as the description thereof proceeds.

In the drawing forming part of this specification:

Figure 1 is a perspective view showing one form of the invention.

Figure 2 is a horizontal section taken on line 2—2 of Figure 1.

Figure 3 is an end elevation showing a modified form of the invention.

Figure 4 is an end elevation showing the bulkhead of Figure 3, with the parts nested and fastened together.

Figure 5 is a view similar to Figure 2 showing a further modified form of the invention.

Referring to the drawing and more particularly to Figures 1 and 2 thereof, the numeral 10 designates in its entirety a portable bulkhead involving the instant invention. The bulkhead

comprises spaced metallic uprights 11 which preferably are channel shaped in section and arranged so that the flanges 12 and 13 of each of the uprights 11 extend rearwardly. An angle member 14 is secured to the webs 15 at the upper margins of the uprights 11 so that the flange 16 of said angle member projects forwardly. An angle member 17 is secured to the webs 15 of the uprights at the lower margins thereof so that the flange 18 of said angle member projects rear-

wardly and constitutes the nailing flange of the merchandise engaging wall of the bulk head by means of which said wall may be secured to a support. Openings 19 are formed in the flange 18 through which nails may be driven into the support.

The uprights 11 and upper and lower angle members 14 and 17 secured thereto thus comprise a metallic frame to which spaced boards B which may be of wood are secured as by means of bolts 20 passing through said boards and the webs 15 of the channel uprights. The boards B preferably extend beyond the ends of the frame and are formed of one piece members although it is to be understood that the length of these boards 15 may vary and they may be formed of sections joined together.

Braces 21 which are preferably channel shaped in section are hingedly fastened to the webs 15 of the uprights by means of the hinges 22. The braces 21 are arranged so that their flanges 23—23 extend rearwardly from the webs 24. Nailing flanges 25 are secured to the lower ends of the webs of the braces 21 preferably by being hinged thereto.

A locking pin 26 is supported by means of a chain 27 fastened adjacent the upper ends of each of the uprights 11.

In the modified form of the invention illustrated in Figure 5 of the drawing, the openings 19 in the horizontal flange 18 of the bottom angle frame member are omitted and in lieu thereof, nailing flanges 28 fastened to the lower ends of the webs 15 of the channel uprights 11 preferably by being hinged thereto are utilized for the purpose of fastening the merchandise engaging wall of the bulkhead to the support. The sacrifice of strength of the bottom angle frame member 17 where openings are formed in the horizontal flange 18 is avoided by this construction.

In the embodiment of the invention illustrated in Figures 3 and 4 of the drawing additional bracing means for the merchandise engaging wall is provided by virtue of which the nailing of the merchandise engaging wall to a support is obviated while avoiding rotation of said wall about the hinged engagement with the bracing members when the wall is subjected to pressure of the merchandise. In the considered embodiment of the invention the bracing means takes the form preferably of channel members 29 hingedly secured to the webs 15 of the uprights 11 as indicated at 30. The web 31 of each of the bracing members 29 terminates short of the free

ends of the flanges 32 whereby said flanges are permitted to engage the outer faces of the flanges 23 of the main bracing members 21. Adjacent the outer ends of the webs there are secured 5 chains 33 which carry pins 34.

It will be observed that aligned openings 35-35 are provided in the flanges 12-13 of each of the uprights 11 and that aligned openings 36-36 are formed in the flanges 23-23 of the bracing members 21. In use the bulkhead is disposed so that the horizontal flange 18 of the bottom angle member 17 rests upon the supporting surface whereupon the merchandise engaging wall of the bulkhead may be fastened to the supporting surface by means of nails or the like extending through either the openings in the horizontal flange 18 or through openings provided in the hinged nailing flanges 28. The braces which have assumed their proper angle position relative to the supporting surface are then nailed or otherwise fastened thereto by means extending through the openings provided in the nailing flanges 25. The bulkhead will then maintain any merchandise in position against displacement or shifting and 15 tendency of the merchandise engaging walls of the bulkhead to rotate under pressure of the merchandise is effectively resisted. By reason of the employment of the hinged nailing flanges, irregularities in supporting surfaces are compensated 20 for. Where the nailing of the merchandise engaging wall to the supporting surfaces is omitted the bracing members 29 are releasably fastened to the bracing members 21 by means of the pins 34 which extend through openings in the flanges 32 and the openings 36 formed in the flanges 23 of the bracing members 21. Tendency of the merchandise engaging wall to rotate under pressure is also resisted by the bulkhead even though the merchandise engaging walls rests free upon a 25 supporting surface.

With reference to Figure 4 of the drawing, it will be apparent that the braces and hinged nailing flanges may be nested relative to the wall or upright members of the bulkhead as to be confined within the vertical planes defining said wall or uprights. By reason of this nesting of the braces, the bulkhead may when not in use be assembled into a compact unit requiring a minimum of space for storage and permitting easy 30 handling thereof. To nest the indicated parts of the bulkhead, the hinged nailing flanges 25 are swung about their pivots so as to be disposed inwardly of the flanges 23. The bracing members 21 may then be swung upwardly about their pivots 35 so as to be received between the flanges 12 and 13 of the uprights 11 where they may be secured by means of the pins 26 which may be passed through the openings 35-35 and the openings 36-36 aligned therewith. Similarly the bracing 40 channels 29 may be swung upwardly between the flanges 12 and 13 of the uprights and be secured thereto by means of the pins 34 which may be passed through the openings in the flanges 32 and through the openings 37 formed in the flanges 65 12 and 13 of the uprights. The braces 21 in the embodiment of the invention illustrated in Figures 1 and 2 of the drawing may similarly be nested with the uprights 11 and be secured thereto by the pins 26.

70 It will be apparent that numerous changes and modifications in the details of the invention will be clear to those skilled in the art. It is intended, therefore, that all such modifications and changes be comprehended within this invention, which is to be limited only by the scope

of the claims appended hereto. For example, the merchandise engaging wall illustrated in Figure 3 of the drawing may be nailed down to a support by providing openings 19 in the horizontal flange 18 of the bottom angle member, or by employing the hinged nailing flanges 28 shown in Figure 5 of the drawing.

We claim:

1. A portable bulkhead comprising spaced channel shaped uprights, spaced horizontal members extending between and fastened to said uprights, braces hinged to said uprights, nailing flanges hingedly secured to said braces, said nailing flanges being swingable to nested position in said braces and said braces being swingable to nested position in said uprights, and means for releasably fastening said braces when nested to said uprights.

2. A portable bulkhead comprising spaced channel shaped uprights, spaced horizontal members extending between and fastened to said uprights, nailing flanges hingedly secured to said uprights, flanged braces hinged to said uprights and having means for fastening said braces to a support, said braces and nailing flanges being swingable to nested position in said uprights, the flanges of said uprights and braces being overlapped in said nested position, aligned openings in said flanges, and pins adapted to extend through said openings for fastening said braces to said uprights.

3. A device of the character described comprising a wall having spaced uprights, means hinged to said uprights adapted to be secured to a support and horizontal members secured to said uprights, braces hinged to said uprights, said braces and said means being swingable relative to said uprights for disposition substantially within the vertical planes defining said uprights, and means for releasably fastening said braces and said uprights together.

4. A device of the character described comprising a wall having spaced uprights, means hinged to said uprights adapted to be secured to a support and horizontal members secured to said uprights, braces hinged to said uprights, flanges hinged to said braces adapted to be secured to said support, said flanges being swingable inwardly of said braces and said braces and said means being swingable relative to said uprights for disposition substantially within the vertical planes defining said uprights, and means for releasably fastening said braces and said uprights together.

5. A device of the character described comprising a wall having spaced uprights, means hinged to said uprights adapted to be secured to a support and horizontal members secured to said uprights, braces hinged to said uprights, said braces and said means being swingable relative to said uprights for disposition substantially within the vertical planes defining said uprights, and means for releasably fastening said braces and said uprights together, said last mentioned means comprising pins carried by said uprights and adapted to extend through aligned openings in said uprights and said braces.

6. A device of the character described comprising a metallic frame having spaced uprights and upper and lower horizontal members connecting said uprights, horizontal members between said upper and lower frame members fastened to said uprights, braces hinged to said uprights intermediate the ends thereof and having

means for securing said braces to a support, and hinged nailng flanges secured to said uprights.

5 7. A portable bulkhead comprising spaced channel shaped uprights, spaced horizontal members extending between and fastened to said uprights, braces hinged to said uprights, nailng flanges hingedly secured to said uprights, nailng flanges hingedly secured to said braces and disposable inwardly of said braces, said braces and said nailng flanges on said uprights being swingable to nested position in said uprights, and means for releasably fastening said braces to said uprights.

10 8. A device of the character described comprising a metallic frame having spaced uprights and upper and lower horizontal members con-

necting said uprights and means for securing said frame to a support, horizontal members between said upper and lower frame members fastened to said uprights, braces hinged to said uprights intermediate the ends thereof, and hinged nailng flanges secured to the free ends of said braces.

15 9. A device of the character described comprising a substantially rectangular metallic frame including channel shaped uprights, braces hinged to said uprights, additional braces hinged to said uprights and adapted to be fastened to said first mentioned braces, all of said braces being swingable to nested position in said uprights, and means securing said braces to said uprights.
